UNITED STATES PATENT OFFICE.

DIEDRICK J. FREESE, OF HIGGINSVILLE, MISSOURI.

WEIGHT-MOTOR.

SPECIFICATION forming part of Letters Patent No. 502,814, dated August 8, 1893.

Application filed June 17, 1893. Serial No. 477,935. (No model.)

To all whom it may concern:

Be it known that I, DIEDRICK J. FREESE, a citizen of the United States, residing at Higginsville, in the county of Lafayette and State of Missouri, have invented a new and useful Weight-Motor, of which the following is a specification.

The invention relates to improvements in weight motors.

10 The object of the present invention is to improve the construction of weight motors, and to provide simple and effective means, whereby heavy weights may be easily and quickly elevated for the purpose of furnishing the motive power.

15 The invention consists in the construction and novel combination and arrangement of parts hereinafter fully described, illustrated in the accompanying drawings, and pointed out in the claims hereto appended.

In the drawings—Figure 1 is a side elevation of a weight motor constructed in accordance with this invention. Fig. 2 is a vertical longitudinal sectional view.

20 Like numerals of reference indicate corresponding parts in both the figures of the drawings.

25 1 designates a main frame, provided at the back with a vertical extension 2, forming a well or way for weights 3 and 4; the main frame has journaled on it a power shaft 5, which carries a drum 6; and extending from the drum are cables 7 and 8, which pass over pulleys 9 and 10 and are connected to the weights 3 and 4. The cable 7 extends upward from the front side of the drum to the top of the weight well or way; and the other cable 8 extends downward from the rear side of the drum and passes around a pulley roll 11 and then upward to the pulley 10. This arrangement of cables equalizes the strain on the drum and enables heavy weights to be employed without racking or straining the gearing. A train of gear wheels 12 connects the power shaft 5 with a drive shaft 13; and the latter is connected by a train of gear wheels 14 with a governor 15, which regulates the speed of the motor and the distribution of the power. The drive-shaft 13 carries a drive

30 45 50 pulley 16 from which motion may be commu-

nicated to any machinery, and one or more drive-wheels or pulleys may be employed. The drum 6 is connected with the lowermost gear wheel 17 of the train 12, by a clutch consisting of a check pawl 18 and a ratchet wheel 19, whereby the gear wheel 17 rotates with the drum when the latter is actuated by the weights. The weights are wound up by a lever 20 and a platform 21, which are fulcrumed on the main frame, and are connected by a rod 22. The lever and the platform are provided at their rearends with longitudinal slots 23 and 24 to enable them to be adjusted longitudinally to regulate the lifting power; and the rod 22 is provided at its ends with clips 25, and is attached to the lever in advance of the fulcrum 26, and to the platform in rear of the fulcrum 27 on an extension 28 of the platform, whereby an upward movement of the lever will force the platform downward, thereby enabling the strength of a person to be utilized to its greatest advantage in assisting his weight to force the platform downward. The adjustability of the connecting rod 22 in connection with the longitudinal slots 23 and 24 enable the desired leverage to be readily obtained.

35 The platform is provided in advance of the ratchet wheel with a pivoted depending spring actuated pawl 29 for actuating the ratchet wheel for winding the cable on the drum. The pawl 29 is held in engagement with the ratchet wheel by a curved resilient inner end 30 of a longitudinally movable rod 31, which is connected by a link 32 with an outer hinged section 33 of the platform. The hinged section 33 is adapted to be swung upward against the main frame, in order to be out of the way after the operation of winding up the weights is completed; and when swung upward, the hinged section 33 of the platform through the link 32 draws the pawl 29 out of engagement with the ratchet wheel. As soon as the outer hinged portion of the platform is lowered to a horizontal position the actuating pawl 29 will be carried into engagement with the ratchet wheel. The longitudinally movable rod 31 is arranged in guide eyes 34 of bolts, and is located on the lower face of the platform.

The lever 20 is provided with a sliding outer section 35, which telescopes into the body of the lever when the winding mechanism is not in use.

5 It will readily be seen that the winding mechanism of the weight motor may be readily adjusted to obtain the desired leverage to enable heavy weights to be conveniently raised; and that the power thus obtained may 10 be readily transmitted to any desired machinery or device to be operated.

Changes in the form, proportion and the minor details of construction may be resorted to without departing from the principle or 15 sacrificing any of the advantages of this invention.

What I claim is—

1. In a weight motor, the combination of a main frame, a power shaft journaled therein, 20 a drum mounted on the power shaft, a drive shaft journaled on the frame, a train of gears connecting the drive and power shafts, a clutch connecting the drum with the train of gears and comprising a pawl and ratchet 25 wheel, a weight, a cable connecting the weight with the drum, a platform fulcrumed on the frame intermediate of its ends and provided with an actuating pawl engaging the ratchet wheel, and a lever fulcrumed on the main 30 frame and located above the platform and connected at a point in advance of its fulcrum with the platform in rear of the fulcrum of the latter, substantially as described.

2. In a weight motor, the combination of a main frame, a power shaft journaled therein, 35 a drum mounted on the power shaft, a drive shaft journaled on the frame, a train of gears connecting the drive and power shafts, a clutch connecting the drum with the train of 40 gears and comprising a pawl and ratchet wheel, a weight, a cable connecting the weight with the drum, a platform fulcrumed on the frame and provided with an actuating pawl engaging the ratchet wheel, and a lever fulcrumed on the frame and located above the 45 platform and connected therewith, substantially as described.

3. In a weight motor, the combination of a main frame, drive and power shafts journaled 50 thereon, a train of gears connecting the shafts, a drum mounted on the power shaft, a clutch connecting the drum with the train of gears and composed of a pawl and a ratchet wheel, a longitudinally adjustable platform fulcrumed on the main frame and provided with a pawl to engage said ratchet wheel, a longitudinally adjustable lever fulcrumed on the frame, and an adjustable rod connecting the lever with the platform and attached to the 55 former in advance of the fulcrum, and to the latter in rear of the fulcrum, substantially as described.

4. In a weight motor, the combination of a main frame, drive and power shafts journaled 60 thereon, a train of gears connecting the shafts, a drum mounted on the power shaft, a clutch

connecting the drum with the train of gears and composed of a pawl and a ratchet wheel, a platform fulcrumed on the main frame and provided with an actuating pawl to engage 70 the ratchet wheel and having a hinged section adapted to be swung upward, and means for connecting the hinged section with the actuating pawl, whereby when the hinged section is swung upward the actuating pawl will be 75 drawn from engagement with the ratchet wheel, substantially as described.

5. In a weight motor, the combination of a main frame, drive and power shafts journaled thereon, a train of gears connecting the shafts, 80 a drum mounted on the power shaft, a clutch connecting the drum with a train of gears and composed of a pawl and a ratchet wheel, a platform fulcrumed on the main frame and having a hinged outer section adapted to be 85 swung upward, an actuating pawl mounted on the platform and engaging the ratchet wheel, a rod slidably mounted on the platform and having a curved resilient rear end connected with the actuating pawl, and a link 90 connecting the front end of the rod with the upwardly swinging section of the platform, substantially as described.

6. In a weight motor, the combination of a main frame, drive and power shafts journaled 95 thereon, a train of gears connecting the shafts, a clutch composed of a pawl and a ratchet wheel, a drum mounted on the power shaft and connected with the train of gears by said clutch, a platform fulcrumed on the main 100 frame and provided with an actuating pawl engaging the ratchet wheel, said platform having an upwardly swinging outer section, a lever fulcrumed on the frame and arranged above the platform and provided with an outer 105 telescoping section, and means for connecting the platform and the lever, substantially as described.

7. In a weight motor, the combination of a main frame, drive and power shafts journaled 110 thereon, a train of gears connecting the shafts, a drum mounted on the power shaft, a clutch connecting the drum with the train of gears and composed of a pawl and a ratchet wheel, a longitudinally adjustable platform fulcrumed on the main frame and provided with a longitudinal slot to receive the fulcrum and having a rearward extension, an actuating pawl carried by the platform and engaging the ratchet wheel, a longitudinally adjustable 115 lever fulcrumed on the main frame and located above the platform and having a longitudinal slot to receive the fulcrum, and a connecting rod provided at its ends with clips arranged on the lever in advance of its fulcrum, and on the rearward extension of the platform, substantially as described.

8. In a weight motor, the combination of a main frame, drive and power shafts journaled thereon, a train of gears connecting said shafts, a governor connected by a train of gears with the drive shaft, a drum mounted on the power 130

shaft, a pulley roll located below the power shaft, cables wound around said drum, one of the cables extending upward from one side of the drum, and the other cable extending downward from the opposite side of the drum, and passing around the pulley roll, and weights connected with the cables, substantially as described.

In testimony that I claim the foregoing as my own I have hereto affixed my signature in the presence of two witnesses.

DIEDRICK J. FREESE.
